UNITED STATES PATENT OFFICE.

FREDERICK J. MATHESON, OF NEWARK, NEW JERSEY.

HAIR-TINTING DEVICE.

Application filed September 4, 1926. Serial No. 133,552.

This invention relates generally to improvements in devices used when dyeing or tinting hair. The object of the invention being the provision of an improved device which will prevent the dye used, especially when dyeing or tinting hair at the roots which has recently grown in of a grey color, so as to prevent the dye used from running onto the hair which has been previously dyed, which will prevent the streaking of the hair which has been previously dyed, tinted, or the like.

Fig. 1 of the drawings, illustrates my improved device in use, applied to the hair of a person.

Fig. 2 is a side elevational view of my improved device.

Fig. 3 is a top plan view thereof.

Fig. 4 is a transverse sectional view taken on the line 4—4 of Fig. 2.

Fig. 5 is a perspective view of my improved device, showing same in an open position.

Fig. 6 is a similar view to that shown in Fig. 5, illustrating a further development of my improved device.

Fig. 7 is a similar view to that shown in Fig. 6, illustrating another development thereof.

As here embodied my improved device comprises a clamp member 10, hinged at one extremity, in the usual well known manner, as at 11, to one extremity of the clamp member 12. The clamp member 10 has attached thereto, at or near its free extremity, the ball member 13, of the usual snap fastener, adapted to engage the socket member 14 of the said snap fastener, which is attached to the clamp member 10, as a means of holding my improved device in a closed position as illustrated in Fig. 2 of the accompanying drawings. The said clamp members 10 and 12, have their lower edges formed with a curvature, as at 15, so as to conform somewhat to the shape or contour of a person's head. The clamp members 10 and 12, have their free extremities notched, as at 16 and 17, respectively, at the upper and lower edge thereof, so as to permit my improved device to be readily opened, so as to be removed from the hair of the person being treated.

In Fig. 6 of the accompanying drawings, the spring 18, provided with a central portion 19 formed or bent curved, and having extended elements 20 and 21, formed corrugated, is attached, as at 22, by a pin or the

like, attached to the clamp members 10 and 12. The pins 22 are positioned in elongated slots 23 formed in the extended elements 20 and 21 of the said spring 18, and are provided with enlarged heads, so as to secure the engagement of the said spring. The above described construction being such as will permit the spring 18 to normally hold my improved device in a tightly closed position, which will more readily prevent the dye used from running onto the hair previously dyed.

In Fig. 7 of the accompanying drawings, the flap members 23, having curved lower edges 24, similar to the above mentioned curvature 15 of the clamp members 10 and 12, are pivotally attached, as at 25, at one extremity, at or near the center of the clamp members 10 and 12. The flap members 23, have formed therein elongated slots 26, adapted to receive the pins 27, attached to the clamp members 10 and 12, and which are provided with enlarged heads, so as to permit the said pins 26 to frictionally hold the flap members 23 in any desired position, so as to accommodate my improved device to the heads of persons of various sizes, as may be accomplished by pivoting the flap members 23, as designated by the dot and dash lines 28.

Having thus described my invention, what I claim as new and desire to protect by Letters Patent of the United States is as follows:

1. A device adapted to prevent hair previously dyed from being streaked when dye or the like is applied to the new grown hair comprising clamp members pivotally attached, said clamp members held in a closed position by a snap fastener, said clamp members provided with curved portions, adapted to conform to the head of a person, a notch provided at the upper edge of the free extremity of the clamp member, a second notch formed in the lower edge of the second clamp member, so as to permit the device to be readily opened.

2. In combination with a device of the class described, a spring attached to a clamp member and a second clamp member, said spring adapted to normally hold the said clamp members in a closed position, said spring provided with a central portion formed curved, and having its extended elements formed corrugated, said spring provided with elongated slots adapted to be en-

gaged by pins attached to the said clamp members, said pins provided with enlarged heads, so as to secure the engagement of the said spring.

5 3. In combination with a device of the class described, flap members pivotally attached at one extremity, at the center of clamp members, said flap members having formed therein elongated slots adapted to 10 receive pins attached to the said clamp members, said pins provided with enlarged heads, so as to permit the said pins to frictionally hold the said flap members in any desired position, as a means of permitting 15 the curved edges of the said flap members to accommodate the head of a person.

4. In a device of the class described, a clamp comprising hinged side members, a projection element of a snap fastener on one 20 of said side members at the free end thereof, and a socket member of a snap fastener on the other side member positioned in registration with said projection element, said side members having an arcuate shaped 25 lower edge adapted to fit the curvature of a head for permitting said clamp to engage the short length of hair and hold the same in upright position extending outwardly from the head.

30 5. In a device of the class described, a clamp comprising hinged side members, and fastening means on the free ends of said hinged side members for holding the latter in closed position, said side members having 35 arcuate edges adapted to conform to the curvature of a head for permitting engage-

ment of short length of hair between said side members in outwardly extended relation to said head.

6. In a device of the class described, a 40 clamp comprising hinged side members, and fastening means on the free end portions of said side members, one of said side members being provided with a notch at the upper portion thereof and the other side member 45 being provided with a notch at the lower portion thereof for permitting said side members to be rotated in opposite directions with respect to each other for disengaging said fastening means. 50

7. In a device of the class described, a clamp comprising side members having arcuate edges adapted to conform with the curvature of a head, a hinge pivotally connecting said side members, fastening means 55 on the free ends of said side members, said side members being adapted to be rotated to position adjacent to each other for clamping strands of hair therebetween and for holding the same in outwardly directed relation 60 to the head, a projection element on one of said side members, and a socket member on the other side member adapted to register with each other when said side members are rotated to adjacent position, the extremities 65 of said side members being provided with non-registering notches for permitting said side members to be rotated to open position for disengaging said projection and socket.

In testimony whereof I have affixed my 70 signature.

FREDERICK J. MATHESON.
